US0D1087887S

(12) **United States Design Patent** (10) **Patent No.:** **US D1,087,887 S**
(45) **Date of Patent:** **** Aug. 12, 2025**

(54) **PORTABLE POWER STORAGE SYSTEM**

(71) Applicant: **Videndum Production Solutions Inc.**,
Shelton, CT (US)

(72) Inventors: **David Pasko**, Middlebury, CT (US);
Andrew Hutton, Dunstable (GB);
Andrew John Sincic, Canoga Park, CA
(US); **Jim Markland**, Stratford, CT
(US)

(73) Assignee: **Videndum Production Solutions Inc.**,
Shelton, CT (US)

(**) Term: **15 Years**

(21) Appl. No.: **29/893,193**

(22) Filed: **May 25, 2023**

(57) **CLAIM**

The ornamental design for a portable power storage system as shown and described.

DESCRIPTION

FIG. 1 is a front perspective view of a portable power storage system.

FIG. 2 is a rear perspective view thereof.

FIG. 3 is a rear view thereof.

FIG. 4 is a front view thereof.

FIG. 5 is a right-side view thereof.

FIG. 6 is a left-side view thereof.

FIG. 7 is a top view thereof; and,

FIG. 8 is a bottom view thereof.

In these drawings, the solid lines illustrate the claimed ornamental design, whereas broken lines, if present, illustrate unclaimed subject matter and form no part of the claimed design.

1 Claim, 8 Drawing Sheets
